UNITED STATES PATENT OFFICE.

JOHN HENRY KOONS, OF LEHIGHTON, PENNSYLVANIA, ASSIGNOR OF ONE-HALF TO HENRY SCHWARTZ, OF LEHIGHTON, PENNSYLVANIA.

FOLDING STRETCHER OR COT.

SPECIFICATION forming part of Letters Patent No. 709,332, dated September 16, 1902

Application filed March 14, 1902. Serial No. 98,185. (No model.)

To all whom it may concern:

Be it known that I, JOHN HENRY KOONS, a citizen of the United States, and a resident of Lehighton, in the county of Carbon and State of Pennsylvania, have invented a new and Improved Folding Stretcher or Cot, of which the following is a full, clear, and exact description.

The object of the invention is to provide a new and improved folding stretcher, cot, or like article which is simple and durable in construction, easily set up, with the parts securely locked against accidental closing, and adapted to be folded into a comparatively small space for storing or transportation purposes.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a plan view of the improvement in an extended position. Fig. 2 is a longitudinal sectional side elevation of the same on the line 2-2 of Fig. 1. Fig. 3 is an inverted plan view of the same, partly closed. Fig. 4 is a transverse section of the improvement on the line 4-4 of Fig. 1. Fig. 5 is an enlarged perspective view of a modified form of the hinge-lock for the cross-bars; and Fig. 6 is a side elevation of another modified form of a hinge-lock, parts being shown in section.

The side rails A of the stretcher, cot, or like article are connected with each other by a suitable cover B, made of canvas, leather, or other similar flexible material, and the said rails are also connected with each other at their ends by cross-bars C, each made in sections C' C², hinged together at C³ and hinged to keepers D, secured to the side rails. A. In order to lock the sections C' and C² in position when in alignment with each other, as shown in Figs. 1, 2, and 4, I provide a locking device consisting preferably of a bar E, secured to the section C² and carrying at its free end a spring-catch E', adapted to engage the wall of an aperture in the other sec-

tion C' to hold the sections C' and C² locked together when extended in a transverse direction, as plainly indicated in Fig. 1. It is understood that the bar E extends from the section C² past the hinge C³ onto the other section C', so that its spring-catch E' can engage the section C' to lock the sections together.

When it is desired to fold the device, then the operator moves the spring-catch E' out of engagement with the section C' to allow the sections C' and C² of the cross-bar to swing into a closed position in an inward direction, as indicated in Fig. 3. Each section of a cross-bar is pivotally connected by a link F with a leg G, pivoted to the corresponding side rail A, the arrangement being such that when the cross-bars are in a folded position then the legs G are folded upon the side rails, and when the device is set up and the side-rails A are moved apart to swing the sections C' and C² of the cross-bars into an extended position then the said links F impart a swinging motion to the legs G, so as to swing the latter into an extended position—that is, into an angular position relative to the side rails—to support the rails and cover a distance above the ground, as will be readily understood by reference to Figs. 2 and 4.

Each of the links F is preferably made in three sections F', F², and F³, of which the sections F' and F² are connected with each other by a hinge F⁴, and the sections F² and F³ are similarly connected with each other by a hinge F⁵, extending at angles, however, to the hinge F⁴. (See Fig. 2.) The section F' is pivoted on the corresponding cross-bar section C' or C², and the section F³ is likewise pivoted on the corresponding leg G; but the pivots of the sections F' and F³ extend at angles to each other—that is, the pivot for the section F' stands vertically, while that for the section F³ stands transversely, as will be readily seen by reference to Fig. 2. It is understood that by making the links F in the manner described an easy and free movement of the sections of the cross-bar and the legs G is possible, so that the legs G swing readily into a folded position on closing the cross-bar sections, and when the device is set up and

the rails are moved apart then the cross-bar sections are readily extended and pull by the links F on the legs G, so as to swing the latter into an active angular position relative to the side rails A.

The locking device for locking the sections C' and C² in an extended position may be differently constructed—for instance, as shown in Fig. 5, in which the bar E², secured to the section C', is provided at its end with an apertured pin E³, extending through an opening in the section C², and the said apertured pin is adapted to be engaged on the outside of the section C² by a hook E⁴, pivoted to the section C². Thus when the hook E⁴ engages the pin E³ then the sections C' and C² are locked in an extended or alined position.

In the modified form shown in Fig. 6 the bar E⁵, secured to the section C', is provided at its free end with a pivoted catch E⁶, adapted to engage the section C², the catch being pressed on by a spring E⁷ to normally hold the catch in engagement with the section C². In either case, however, the locking device serves to hold the sections C' and C² in an alined transverse position to hold the side rails A the desired distance apart—that is, with the cover B properly stretched from one side rail to the other.

In order to accommodate the spring-catch E' when the device is folded, I form the legs G and rails A with apertures (see Fig. 2) for the spring-catch to pass in on moving the rails A into a closed position.

Having thus described my invention, I claim as new and desire to secure by Letters Patent—

1. A folding stretcher, cot or like article, comprising side rails, a flexible cover secured to the side rails, cross-bars made in sections hinged together and pivoted to the side rails, legs hinged on the side rails, and links connecting the cross-bars with the said legs, to swing the latter into a closed position on moving the rails toward each other to fold the device, and to swing the legs into an angular active position on moving the rails apart, as set forth.

2. A folding stretcher, cot or like article, comprising side rails, a flexible cover secured to the side rails, cross-bars for connecting the side rails with each other, each cross-bar being made in sections pivoted together and to the side rails by vertical pivots, legs hinged

to the side rails, and sectional links, each pivoted to a leg by a horizontal pivot and to a section of the cross-bar by a vertical pivot, as set forth.

3. A folding stretcher, cot or like article, comprising side rails, a flexible cover secured to the side rails, cross-bars for connecting the side rails with each other, each cross-bar be-

ing made in sections pivoted together and to the side rails by vertical pivots, legs hinged to the side rails, and sectional links, each connecting a leg with a section of the cross-bar, each link being made of three sections connected with each other by hinges and pivoted to the cross-bar sections by vertical pivots and to the legs by horizontal pivots, as set forth.

4. A folding stretcher, cot or like article, comprising side rails, a flexible cover secured to the side rails, cross-bars for connecting the side rails with each other, each cross-bar being made in sections pivoted together and to the side rails by vertical pivots, legs hinged to the side rails, sectional and pivoted links, each link being pivoted to a leg by a horizontal pivot and to a section of the cross-bar by a vertical pivot, and a locking device for each cross-bar, to lock the sections thereof in an extended position, as set forth.

5. A folding stretcher, cot or like article, comprising side rails, a flexible cover secured to the side rails, cross-bars for connecting the side rails with each other, each cross-bar being made in sections pivoted together and to the side rails by vertical pivots, legs hinged to the side rails, sectional links pivoted together by pivots at right angles to each other, each link being pivoted to a leg by a horizontal pivot and to a section of the cross-bar by a vertical pivot, and a locking device for each cross-bar, to lock the sections thereof in an extended position, each locking device consisting of a bar fastened to one section and having means at its free end to engage the other section of the cross-bar to lock the sections in alinement, as set forth.

6. In a folding stretcher, cot or the like, the combination with side rails having openings therein and legs pivoted to the side rails adjacent to the openings thereof and provided with an opening near its pivoted end, of sectional and hinged cross-bars pivoted at their ends to the side bars, one section of said bars being provided with an opening, a bar secured at one end to one of the sections of each of the cross-bars and provided at its free end with a catch adapted to enter the opening in the other section when the sections are in alinement and to enter the openings of the legs and side rails when the device is folded, and links pivoted to the cross-bars and to the legs, as set forth.

In testimony whereof I have signed my name to this specification in the presence of two subscribing witnesses.

JOHN HENRY KOONS.
